DESIGN FOR A CONFECTIONERY PRODUCT

Alfred Lowenstein, New York, N. Y.

Application December 29, 1939, Serial No. 89,194

Term of patent 14 years

To all whom it may concern:

Be it known that I, Alfred Lowenstein, a citizen of the United States, residing at Bronx, New York, in the county of Bronx and State of New York, have invented a new, original, and ornamental Design for a Confectionery Product, of which the following is a specification, reference being had to the accompanying drawing, forming part thereof.

In the drawing:

Fig. 1 is a front view of a confectionery product, showing my new design.

Fig. 2 is a side view thereof.

Fig. 3 is a top plan view.

I claim:

The ornamental design for a confectionery product, as shown.

ALFRED LOWENSTEIN.
